UNITED STATES PATENT OFFICE.

ANDREW B. MILLER, OF BALDWIN, WISCONSIN, ASSIGNOR OF ONE-FOURTH TO RASMUS JOHNSON, ONE-FOURTH TO HORACE C. NELSON, AND ONE-FOURTH TO EDWARD CHRISTENSEN, ALL OF BALDWIN, WISCONSIN.

DRY-CLEANING MACHINE.

1,170,088.

Specification of Letters Patent.

Patented Feb. 1, 1916.

Application filed April 29, 1915. Serial No. 24,786.

To all whom it may concern:

Be it known that I, ANDREW B. MILLER, a citizen of the United States, residing at Baldwin, in the county of St. Croix and 5 State of Wisconsin, have invented a new and useful Dry-Cleaning Machine, of which the following is a specification.

My invention relates to machines for dry-cleaning clothes, and the object is to provide an economical and fast-working machine of such construction that by making slight adjustments of some of the parts the same one machine will clean the clothes by gasoline and then extract the gasoline from 10 the clothes, and when so desired the machine may be used as an ordinary clothes washing machine.

In the accompanying drawings,—Figure 1 is a top view of my improved machine with 20 its cover removed. Fig. 2 is an edge view of one of the eccentrics with its yoke and rod employed in the machine. Fig. 3 is a left hand side view of what is shown in Fig. 2. Fig. 4 is an approximately diametrical 25 vertical section of the machine with its cover on it. Fig. 5 is a top view of the crosshead 37, 38 and 38^a in Fig. 4.

Referring to the drawings by reference numerals, 1 designates the main tub, it is 30 riveted at 2 to a bottom 3, which rests on legs 4 and is provided with radial grooves 5 and a depression 6 having a pet-cock or valve 7 through which to empty the gasoline out from the machine. The tub is also 35 provided with a cover 8 having a handle 9.

Spaced within the tub 1 is a perforated cylinder 10, 11 indicating the perforations. Said cylinder has its bottom 10^a fixed on a central vertical shaft 12, whose lower end is 40 journaled in a ball-bearing 13 in the bottom of the tub, and the upper end is journaled in the leg of a T-shaped member 14, in whose upper portion and in bearings 16, 17 fixed on the tub is journaled a horizontal operating 45 shaft 15, which is provided with a handle 19 and a pulley 18 so it may be turned by either hand power or a belt where motive power is available.

Slidably fitted on the shaft 15 and a 50 feather key 20 in same (see Fig. 1) is a bevel pinion 21, having a set-screw 22 by which it may be secured on the shaft either in mesh with a bevel gear ring 23 fixed about the top of the cylinder 10, or out of

mesh with the same. In like manner a 55 bevel gear 24 is slidable on the shaft 15 and a feather key 25 therein and provided with a set-screw 26 which may hold the gear either in mesh or out of mesh with a bevel pinion 27 fixed on the vertical shaft 12. 60 Fixed on the shaft 15 are also two eccentrics 28, 28, each of which operate a yoke 29, which it to some extent guides by flanges 28^a (see Fig. 3) engaging at opposite sides of the yoke. In each yoke is fixed the upper end of a rod 30 of a pounder piston 31, which piston operates in a bottomless cylinder 32 having its upper end closed by a head 33, which is provided with apertures 34 to prevent vacuum above the piston; it is 70 also provided with a hub 35 slidable on the pounder rod, or piston rod, 30. Upon said hub presses the lower end of a coil spring 36, whose upper end engages a cross-head 75 slidable on the shaft 12 and composed of a middle section 37 and two detachable sections 38 and 38^a, which are secured to the dasher rods by pins 39 or other suitable means. They are also detachably secured to the section 37 by removable pins 40, having 80 handles 40^a, through overlapping lugs of the sections; said sections being also steadied against each other by abutting faces 41 to prevent turning movement on the pins.

42 is a collar on the shaft 12 to limit the 85 downward movement of the central member of the cross-head when the other members are removed from it.

42^a is a collar on the horizontal shaft to prevent the adjacent journal bearing from 90 getting forced endwise by the meshing gears 24, 27.

The upper end of the cylinder 10 is steadied by brackets 43 having rollers 44 in light contact with the outer side of the gear 95 ring 23.

As best shown in Figs. 2 and 3, each yoke 29 is made up of a lower member fixed to the rod 30 and an upper member hinged to the lower member at 45 and having its 100 other end secured by a thumb-nut 46 and a bolt 47 placed in a gap 48 in the end of the upper member and having its lower end pivoted at 49 in a gap 50 in the lower member.

In the operation of the machine for dry-cleaning, the tub is filled about half full of gasoline, the clothes placed in the cylinder 10, the pounders are placed upon them and 105

the yokes adjusted upon the eccentrics; the gear 24 is put out of mesh and the pinion 21 into mesh, the cover 8 is adjusted and the shaft 15 rotated. During such rotation the pinion 21 rotates the cylinder slowly while the pounders keep moving up and down so as to agitate and pound the clothes while the pistons in the pounders alternately drive the gasoline downward and suck it upward through the clothes. It will hence be understood that when the clothes stop the downward stroke of the hollow pounder members the spring 36 will yield and let the pistons go farther down, and when the pistons move upward again the springs prevent upward movement of the hollow pounder member until the piston has operated to suck gasoline through the clothes. It should also be understood that as only the cylinder 10 rotates and not the pounders with it, the clothes are to some extent rubbed between the pounders and the bottom of the cylinder, and that all these various movements and actions combine in removing the dirt from the clothes. When the clothes are thus cleaned, the cover 8 is removed, the nuts 46 loosened, the bolts 47 swung out of the upper gaps 48, the yokes opened, the pins 40 removed and the members 38, 38^a with the pounders and yokes removed from the tub or machine. Next the gasoline is removed by opening the valve 7. The pinion 21 is then moved out of mesh and the gear 24 moved into mesh with the pinion on the vertical shaft so that a much greater speed of the cylinder is obtained, the shaft 15 is then rotated until the gasoline in the clothes is extracted by centrifugal force and removed from the tub by gravitation when the valve 7 is opened after the extracting is completed. This is the operation for each lot of clothes to be dry-cleaned, and after such cleaning the clothes are of course removed from the cylinder.

If the machine is to be used for common clothes washing, the operation is the same as that already described for dry-cleaning, with the only exception that instead of gasoline water and soap, and if so desired some kerosene may be used.

What I claim is:

1. In a machine of the class described, the combination with a cylindrical tub, having in its lower part an outlet valve and on its top a cover, a vertical shaft journalized centrally upon the bottom of the tub, a member having a vertical journal box for the upper end of said vertical shaft and also integral therewith a box for a horizontal shaft, two other journal boxes secured to the top of the tub at diametrically opposite points thereof, a horizontal operating shaft mounted in said two bearings and in the first mentioned horizontal bearing, and means at one end of said horizontal shaft for applying

rotary power to it; a bevel gear and a bevel pinion slidably keyed on the horizontal shaft and provided with means for holding each of them in two different positions on the shaft, a pinion fixed on the vertical shaft in a position to be engaged by the bevel gear, a perforated cylinder open at the top and having a bottom fixed on the lower end of the vertical shaft and at its upper end an annular bevel gear in a position to be engaged by the bevel pinion on the horizontal shaft; a cross-head slidable on the vertical shaft and having two oppositely directed radial members, two pounders arranged one below each radial member and connected thereto, means on the horizontal shaft for imparting vertical reciprocating movement to the cross-head, and operative connection between said means on the shaft and the cross-head.

2. In a machine of the class described, the combination with a cylindrical tub having a cover and in its lower portion an outlet valve, a vertical shaft journalized centrally upon the bottom of the tub, a member having a bearing for the upper end of said vertical shaft and also integral therewith a horizontal bearing, a horizontal operating shaft journalized in the latter bearing and having also two other bearings secured to the top of the tub one near each end of the shaft, means on said horizontal shaft for imparting rotary movement to it, a bevel gear and a bevel pinion slidably keyed on the horizontal shaft and provided with means for holding each of them in two different positions on the shaft, a pinion fixed on the vertical shaft in a position to be engaged by the bevel gear on the horizontal shaft, a perforated cylinder open at its top and having its bottom fixed on the lower end of the vertical shaft, and its upper end provided with a circular rack in a position to be engaged by the bevel pinion on the horizontal shaft; a cross head slidable on the vertical shaft and having two oppositely directed horizontal radial arms, two dashers having rods fixed in said radial arms, means on the horizontal shaft adapted to impart vertical reciprocating movement of the cross-head and pounders, and operative connection between said means on the shaft and the cross-head; said operative connection and said radial arms of the cross-head being easily detachable from the horizontal shaft and from the cross-head.

3. In a machine of the class described, the combination with an outer tub designed to stand still, of a drive shaft journalized across the top thereof and having slidably held thereon a small and a large bevel gear, a block forming a horizontal bearing for said shaft near the large gear and forming also a vertical bearing, a vertical shaft journalized in said vertical bearing and centrally upon

- the bottom of the tub; a small bevel gear fixed on the vertical shaft in position to be driven by the large bevel gear on the drive shaft; a perforated inner tub having its bottom centrally secured on the vertical shaft and its upper edge provided with an annular bevel gear arranged to be engaged by the small bevel gear on the drive shaft when so desired; pounders arranged within the inner tub and having pounder rods with yokes at the upper ends, eccentrics fixed on the horizontal shaft and operating in the yokes to reciprocate the pounders; said yokes being easily detachable from the eccentrics; a cross-head slidable on the vertical shaft and having horizontal arms detachably secured to the cross-head and fixed to the pounder rods; rollers mounted in the upper end of the outer tub for guiding the upper end of the inner tub, and means for rotating the drive shaft.
4. In a machine of the class described, the combination with an outer tub designed to stand still, of a drive shaft journaled across the top thereof and having slidably held thereon a small and a large bevel gear, a block forming a horizontal bearing for said shaft near the large gear and forming also a vertical bearing, a vertical shaft journaled in said vertical bearing and centrally upon the bottom of the tub, a small bevel gear fixed on the vertical shaft in position to be driven by the large bevel gear on the drive shaft; a perforated inner tub having its bottom centrally secured on the vertical shaft and its upper edge provided with an annular bevel gear arranged to be engaged by the small bevel gear on the drive shaft when so desired; pounders arranged within the inner tub and having pounder rods with yokes at the upper ends, eccentrics fixed on the horizontal shaft and operating in the yokes to reciprocate the pounders; said yokes being easily detachable from the eccentrics; a cross-head slidable on the vertical shaft and having horizontal arms detachably secured to it and fixed to the pounder rods; rollers mounted in the upper end of the outer tub for guiding the upper end of the inner tub, and means for rotating the drive shaft; said pounders being each composed of a pounder rod, a piston fixed at the lower end thereof and a downwardly open suction chamber fitting about the piston and having a perforated top with a central hub slidable on the rod, and a compressible coil spring encircling the rod between the arm of the cross-head and said hub of the top of the suction chamber.
- In testimony whereof I affix my signature, in presence of two witnesses.
